UNITED STATES PATENT OFFICE.

CHARLES FELSKY, OF KOKOMO, INDIANA, ASSIGNOR TO PLANHARD MANUFACTURING COMPANY, OF KOKOMO, INDIANA, A CORPORATION OF INDIANA.

CARBURETER.

1,104,975.

Specification of Letters Patent.

Patented July 28, 1914.

Application filed October 12, 1910. Serial No. 586,610.

To all whom it may concern:

Be it known that I, CHARLES FELSKY, a citizen of the United States of America, and a resident of Kokomo, county of Howard, and State of Indiana, have invented a new and useful Improvement in Carbureters, of which the following is a specification.

My invention relates to vaporizers and mixers for internal combustion engines and has for its principal objects the making of a carbureter for such engines which will supply the proper mixture of gas and air at all engine speeds, and which will, at the same time, be economical as to the use of gasoline or other fuel, adapting itself automatically to the various running conditions of the engine; have a minimum of manual adjustments, and those of a most simple character, and be of such simple construction as to make it easy to manufacture and to maintain.

In my invention I employ valves exposing equal areas to atmospheric pressure and eliminate thereby the use of more than one size of drill in making the valve openings, thereby decreasing the time and hence the cost of manufacture. This improvement combined with the use of balls of equal size and weight, enables me to produce an article which combines cheapness with simplicity of construction.

In the drawings which accompany and form a part of this specification: Figure 1 is a vertical sectional view of my carbureter taken on the line 1 of Fig. 2; Fig. 2 is a horizontal sectional view of the same taken on the line 2 of Fig. 1; Fig. 3 is a vertical sectional view of the lower portion of an alternative form of my carbureter taken on the line 3—3 of Fig. 4; Fig. 4 is a horizontal sectional view of the same taken on the line 4 of Fig. 3; Fig. 5 is a horizontal sectional view of a portion of my device taken directly over one of the valves; Fig. 6 is a sectional view of the same taken on the line 6 of Fig. 5.

Referring to Figs. 1 and 2, the parts 1, 2, 3 and 4 form the body of the main framework of my carbureter. These parts are preferably cast of aluminum, although, of course, they may be made in any other suitable way or of any other suitable material.

Part 1 is provided with an internal screw threaded opening 4 for facilitating its attachment to the intake pipe of the engine.

Within the neck or tube leading from the intake pipe of the engine there is a throttle valve 5, which I preferably make in the general form of a stovepipe damper. This damper plate is secured to the shaft 6 with in the part 1, which shaft carries at its outer extremity the lever 7 for the attachment of the throttle valve rod by which the engine is manually controlled by the operator. Mounted, also, upon the shaft 6 there is a lever 8 which turns with the shaft. This lever 8 is L-shaped and its outer end serves to engage the lug 9 projecting from the part 1 in such a manner as to limit the movement of the shaft and its valve plate, to approximately a 90 degree movement. By changing the angular position of the operating lever 7 with respect to the stop lever 8 on the shaft 6, the lever 7 is readily adapted to receive its push or pull from any direction at right angles with the shaft 6.

The part 2, together with the part 3, forms the float chamber of the carbureter. Part 2 engages part 1 by the screw threads, as clearly indicated. The float chamber 10 is annular in form and within it is mounted the float 11 which may be of cork, wood, hollow metal, or any other suitable substance of smaller specific gravity than the liquid fuel to be used. This float is mounted by bolt 12, or bolts, on the lever 13 which is pivoted on the transverse rod 14 extending across the fuel intake chamber 15. The fuel intake chamber 15 is offset from, but integral with, the float chamber 10. On the outer end of the lever 13 there is carried a cone valve 16 which serves to open or close the passage 17 through which the liquid fuel is supplied. The valve 16 is mounted on a light vertical rod of brass provided with a spherical enlargement which engages loosely with the seat in the lever 13 and is held in place by a hollow nut 19, as indicated. By this construction there is provided a flexible mounting for the valve 16, allowing it to seat itself naturally when depressed. Access to the valve is provided by means of the screw cap 20, which closes the upper part of the fuel intake chamber. Gasoline or other fuel is supplied to the carbureter through the passage 17, suitable pipes terminating in the coupling 21 leading to the fuel tank or reservoir. As soon as the gasoline within the float chamber reaches a predetermined level, the float 11 is raised, which depresses 110

the cone valve 16, thus closing off the supply of more fuel. The withdrawal of fuel from the float chamber allows the cone valve 16 to open slowly, thus admitting more fuel. In this way the level of the gasoline within the float chamber is maintained at an approximately fixed position.

The part 3 is provided with an internal screw threaded flange 22, the screw thread on which engages an external screw threaded portion of the part 1. As the float chamber of the part 2 lies between the lateral flange 23 projecting from the part 1, and the lateral flange 24 projecting from the part 3, the float chamber is securely clamped in place between these two flanges when the screw threaded portion 22 of the part 3 is screwed home on part 1. In order to prevent a fuel leakage the gasket 25, preferably of tubular copper, filled with packing, is provided between the flange 24 and the lower part of the float chamber. Carried upon a tubular transverse member 26, of the part 3, is a cup-shaped spray nozzle 27, which engages the transverse tube 26 by means of a screw thread, as shown, and is, therefore, readily removable for cleansing purposes or for renewal. This spray nozzle has an enlarged opening 28 at its upper end, which opening communicates through the needle valve passage 29 with the passage 30 of the transverse member 26. There is thus afforded a free passage for the fuel from the float chamber 10 to the cup 28 of the spray nozzle, and the gasoline will, therefore, rise in the cup to the same level as in the float chamber. The passage 29 may be closed to a greater or less extent by the needle valve 31, which is screw threaded, as shown, and provided with a stuffing gland 32 which may be packed to prevent leakage of fuel. A suitable thumb screw 33 provides ready means for adjusting the needle valve within the passage, thus regulating the normal flow of fuel through the spray nozzle. Surrounding the stem of the needle valve 31 there is an annular passage 34 which forms the normal air intake; air is thus taken in from the bottom of the carburetor and led up through the passage 34 around the spray nozzle 27. The passage 34 is constricted so as to form a strangling nozzle 35 which is on a level with the upper edge of the spray nozzle. By this means the air, as it is drawn in through the carburetor, rushes by the spray nozzle with a maximum velocity and mixes perfectly with the fuel vapor that is being drawn through the nozzle. Surrounding the passage 34 there is a passage 36 through which air may be admitted from below the carburetor through the auxiliary passages 37. These auxiliary passages are normally closed by means of ball valves 38 held by gravity against the seats provided in the member 39. The member 39 is cast

of brass or bronze and is perforated with a series of holes 37, all of the same diameter. These holes are countersunk to form seats for the balls 38, and the member 39 is externally screw threaded to engage the internal screw thread in the member 3, as shown. As is indicated, member 39 may be screwed into or out of the member 3, thereby increasing or diminishing the distance between the top of the balls and the lower surface of the transverse inward projection of part 3, to adjust the lift of the balls above the valve seat. I preferably make the balls of bronze and make them of the same size and weight, the passages 37 being all of one diameter, the balls being lifted to increased heights and admitting relatively greater quantities of air as the suction increases with the engine speed, thereby adjusting automatically the supply of air to the engine speed at all times. The passage 36, like the passage 34, entirely surrounds the fuel nozzle and is constricted at a point just above the fuel nozzle so that air coming in through the auxiliary passages will unite more completely with the vapor or spray emerging from the spray nozzle. The cup 28, which is just above the needle valve, affords a reservoir for a small amount of gasoline during the periods of idleness of the engine, and the first suction stroke of the engine in cranking throws the accumulated gasoline out of this priming cup and allows it to mix freely with the incoming air, thus giving an initial charge of sufficient richness to cause the first explosion with a certainty, the effect produced being practically the same as though the engine were primed by an external means.

By the concentric form of the normal and high suction air passages, the rich mixture of carbureted air through the normal air passages retains, to a considerable extent, its cylindrical form and is surrounded by a concentric envelop of unmixed air from the high suction air passages as it passes upward through the opening 4. The advantage of the arrangement of parts securing this condition, is that the gasoline vapor does not condense upon the inner surface of the walls of the pipe, leaving the carburetor, because the vapor itself is held insulated in the center of the pipe and does not touch the walls until after it has proceeded so far as to find the walls warmed by the engine, and therefore not producing condensation.

At 40 I show a plunger which may be depressed by the lever 41 so as to push the float 11 down and thereby raise the cone valve 16. By this operation gasoline is allowed to enter the float chamber above its usual level and thus flood the carburetor when such is desired.

The stem portion of the part 3, inclosing the needle valve 31, is threaded on its free

extremity to receive the thumb nut 43. The part 4 is provided with a circular opening to inclose the passages 37 and 34 and is held in place over these openings by the nut 43.

5 The advantage of the circular form of part 3, which permits of the part 4 entirely inclosing all of the air intake openings and passages within the cylindrical space of part 3, is that the air intake passage 45 may be carried to a suitable source of air for feeding the carbureter. In automobile work the carbureter is located in a rather dusty position and the air intake 45 may be carried under the seat or higher in the car if 10 desired, to be above the dust of the road.

15 Referring now especially to Figs. 3, 4, 5 and 6, I have shown an alternative form of valve for the admission of air at high engine speeds. Instead of providing a member 20 39 in which a series of apertures are carried, I cast the part 3 in the form as shown in Figs. 3 and 4, and provide tapped openings for the admission of the tapped individual valve seats 39'. These seats are 25 made of brass and are provided with openings 37' of equal diameters. The balls 38 are all of the same size and weight. It is obvious that with this method of manufacture I may adapt with great facility a given 30 carbureter to a given engine, for the holes in the ball seats may be reduced to any desired degree or may be completely closed, for, as is shown in Figs. 5 and 6, I may insert the blind seat 39'', thus closing completely one or any number of valves, should 35 a particular carbureter be found to supply air too freely at high engine speeds for a particular engine. The ease with which this modification of my carbureter may be 40 adapted to all engines forms a feature of great convenience in manufacture and in practical use.

It is obvious that certain changes may be

made in the details of my carbureter without departing from the spirit of my invention.

Having thus described my invention, what I claim as new and desire to secure by United States Letters Patent is as follows:

1. In a carbureter, a normal air passage; 50 a spray nozzle in said normal air passage; an auxiliary air passage; an annular valve seat member containing a plurality of valve openings in said auxiliary air passage; ball valves normally closing said openings; a 55 member for limiting the lift of said balls; means for adjusting the distance between said valve seat member and said limiting member to vary the lift of said balls; means for locking said members together in their 60 adjusted position, and an intake member common to all of said valve openings held in place by said locking means.

2. In a carbureter, a spray nozzle; a passage surrounding said spray nozzle for the 65 normal admission of air; an auxiliary passage surrounding said normal air passage for the admission of air at high engine suction; an annular valve seat member with a plurality of valves for normally closing said 70 auxiliary passage; a member for limiting the lift of said valves; screw-threaded means for adjusting the distance between said valve seat member and said limiting member to vary the lift of said valves; 75 means for locking said members together in their adjusted position, and an intake member common to both said passages held in place by said locking means.

Signed by me at Kokomo county of Howard and State of Indiana in the presence of two witnesses.

CHARLES FELSKE.
